APPARATUS FOR DEMONSTRATING SOUND-ABSORBING PROPERTIES

Application filed June 19, 1929. Serial No. 372,013.

This invention relates to improvements in apparatus for demonstrating the sound-absorbing properties of various materials and constructions.

- 5 • One object of the invention is to provide a compact portable apparatus which may be used to demonstrate readily and audibly the sound-absorbing properties of various sound-absorbing materials and facing materials.
- 10 10 Other objects relate to various features of construction and arrangement of parts which will be apparent from the consideration of the following specification and accompanying drawings wherein,
- 15 15 Fig. 1 is a longitudinal cross-sectional elevation of one embodiment of my improvements, the section being taken along the line 1—1 of Fig. 2.
- 20 20 Fig. 2 is a transverse sectional elevation taken along the line 2—2 of Fig. 1.
- 25 25 Figs. 3 and 4 illustrate two types of facing materials in tubular form which may be used in conjunction with different sound-absorbing materials.
- 30 30 Fig. 5 is a side elevation of a sound absorbing cylinder.
- 35 35 In acoustical construction work it frequently is desirable to demonstrate sound-absorbing qualities of various kinds of acoustical construction in sound-absorbing materials to those unfamiliar with acoustical correction problems so that they may judge of the comparative qualities of such materials and constructions. A device for this purpose should be compact so that it may be transported conveniently and should be so constructed that various acoustical constructions and sound-absorbing materials may be demonstrated quickly so that a comparison 40 of their sound absorbing qualities can be perceived.

In the drawings, 10 is an outer casing which in the form shown in Fig. 1 is open at its left hand end and at its right hand end is provided with a wall 11. A transverse partition 12 divides the casing interior into compartments 13 and 14. Positioned within compartment 14 is a box 15, preferably of metal, having mounted therein a sound-emitting device, such as an electric

bell 16 of conventional construction. Also housed within said box is a dry cell 17 for operating the bell 16 when the push button 18 is pressed. The remaining space in the box is filled with sound-absorbing material 19 which may be felted wood fiber known as balsam-wool or hair-felt or the like, which should be of sufficient thickness and so compacted that it will not transmit the vibrations or sound set up by the sound-emitting device to the outer case 10, and whereby the sound or vibrations will pass through the tube 20 which forms a sound-passage from the chamber in which the bell is located to the chamber 13.

Secured to the walls 11 and 12, as by soldering or welding or other approved construction, are tubes 21, 22, 23, and 24. Tube 21 is arranged concentrically with the axis of the passage 20, as shown in Fig. 1. The wall 11 is apertured at the outer ends of the tubes 20-24, inclusive.

In conjunction with the apparatus shown there may be prepared a number of cylinders of different sound-absorbing qualities, for demonstration purposes. In Fig. 1 a cylinder 25 is shown, which may be of plaster or plaster-like material, and provided with a central longitudinal passage 26 therethrough which registers with the tube 20. The cylinder 25 may be enclosed in a protecting metal sheath 27, which sheath preferably extends over one end of the cylinder, as shown at 28, the end of the sheath having a central opening in registration with the passage 26.

As will be apparent, when the bell or an equivalent device is operated, the sound will pass through the tube 20 into the passage 26 of the cylinder 25, and the sound-absorbing characteristics of the material of which the cylinder is made may be detected by an acoustimeter, or by the ear.

The cylinder 25 can readily be withdrawn from the supporting tube 21 and another cylinder, formed of different sound-absorbing material, may be inserted for the purpose of comparison. For instance, a second cylinder 29, having a central opening 30 may be formed of balsam-wool, hair felt, or other

material having recognized sound-absorbing qualities and may be withdrawn from the storage tube 22 and placed in the testing tube 21. By operating the bell or other device 16, the sound-absorbing quality of said material can be demonstrated.

- My device is especially useful for testing facings for sound-absorbing materials. For this purpose a tube or cylinder 23' is made 10 of the facing material which it is desired to test, such as perforated metal, as shown in Fig. 3. Said cylinder may be slipped into duct 30 in alignment with tube 20, to serve as a facing for sound-absorbing material 29. 15 An imperforate metal tube 24' is shown in Fig. 4. The tubes or cylinders are readily replaceable and interchangeable so that they may be tested in rapid order, and they may be stored in the storage tubes 23, 24. The 20 entire sound-absorbing construction also may be removed as a unit and another may be inserted.

It will be understood that any number of cylinders formed of different sound-absorbing 25 materials may be employed and additional tubes of different facing materials may likewise be used for making comparison. With the device shown, the listener hears practically only that sound which 30 emerges from the duct 26 or 30, as the case may be, which is a continuation of duct 20 since the sound-absorbing and vibration-absorbing construction used prevents practically any sound or vibrations from passing 35 through the walls of the device to the listener. If desirable, the bell may be replaced by a sound-emitting device in which the intensity, quality and tone may be controlled.

The casing 10 is preferably provided with 40 an end cover 31, which may be hinged at 32 and provided with any suitable fastening means 33 for holding the cylinders in place while the apparatus is being carried. Where a larger number of cylinders of sound-absorbing 45 materials or of facing materials is desired to be carried, the casing may be enlarged to provide space for the necessary storage tubes.

Although I have shown and described a 50 certain embodiment of the present invention for the purpose of illustration, it will be seen that various changes may be made therein without departing from the spirit of the invention as defined in the appended 55 claims.

What I claim is:

1. Apparatus of the class described, comprising a vibration absorbing construction, a controllable sound generating device therein, a duct for conveying sound from said device and a member to be demonstrated having a passage therethrough in communication with said duct.

2. An acoustic demonstration device comprising in combination a vibration absorb-

ing construction, a controllable source of sound encased therein, a duct for conveying sound from said source, and an independent unit comprising a second duct communicating with said first duct and having a sound-absorbing wall. 70

3. Apparatus of the class described comprising a vibration absorbing chamber, a controllable sound generating device therein, a duct for conveying sound from said device, and a plurality of members having longitudinal passages therein adapted to be placed in communication singly with said duct, the walls of said passages being formed of material to be demonstrated. 75

4. An acoustic demonstration device comprising in combination a vibration absorbing construction, a controllable source of sound encased therein, a sound outlet duct therefor a second duct member having a sound-absorbing wall, and interchangeable facings for said absorbing wall forming extensions of said first duct. 80

5. Acoustic demonstration apparatus comprising a vibration absorbing construction, a controllable sound generating device therein, a duct for conveying sound from said device, a member having a passage therethrough adapted to be placed in communication with said duct, the wall of said passage being formed of sound absorbing material, and interchangeable facing members adapted to be inserted singly in said passages. 90

6. Apparatus of the class described comprising a casing having an apertured end wall, a transverse partition in said casing defining two chambers, vibration absorbing material in one chamber, a controllable sound generating device encased within said material, a duct for conveying sound from said device to said other chamber, supporting means disposed between said partition and said end wall, and a member having a longitudinal passage therethrough slideable 105 into said second chamber through the aperture in said end wall, said member being guided by said supporting means for effecting the registration of said passage with said duct. 110

7. An acoustic demonstration device comprising a casing having a transverse apertured partition therein defining two chambers, vibration absorbing material in one chamber, a controllable sound emitting device encased within said material, a duct for conveying sound from said device through the aperture of said partition, said casing having an end wall provided with a plurality of openings, one of said openings being aligned with the aperture in said partition, supporting members in said second chamber each extending from adjacent one of said openings in said end wall to said partition and demonstration members having longi- 120 125 130

tudinal passages therethrough removably carried by said supporting members, each of said demonstration members being adapted to be inserted through the opening aligned with said duct whereby the longitudinal passage thereof forms an extension of the duct.

In testimony whereof, I have subscribed my name.

CHARLES F. BURGESS.
